Primary Examiner—Janice E. Seeger*Attorney, Agent, or Firm*—Evenson, McKeown, Edwards & Lenahan, PLLC[57] **CLAIM**

The ornamental design for a small workshop table, as shown and described.

DESCRIPTION

FIG. 1 is a perspective view of a small workshop table according to my invention, showing the front, top and left sides thereof;

FIG. 2 is a front elevational view thereof;

FIG. 3 is a top plan view thereof;

FIG. 4 is a bottom plan view thereof;

FIG. 5 is a right side elevational view thereof, the left side elevational view being a mirror image thereof; and,

FIG. 6 is a rear elevational view thereof.
